DESIGN FOR A COMBINED RADIO CABINET, PHONOGRAPH CABINET, AND SECRETARY

William J. Gillule, Brooklyn, N. Y.

Application October 12, 1936, Serial No. 65,254

Term of patent 14 years

To all whom it may concern:

Be it known that I, William J. Gillule, a citizen of the United States, residing at Brooklyn, in the county of Kings and State of New York, have invented a new, original, and ornamental Design for a Combined Radio Cabinet, Phonograph Cabinet and Secretary, of which the following is a specification, reference being had to the accompanying drawing, forming part thereof.

The single figure in the drawing shows a front perspective view of the combined radio cabinet, phonograph cabinet and secretary of my new design.

In the combined radio cabinet, phonograph cabinet, and secretary of my new design, the radio loud speaker is in the lower lefthand portion, the radio cabinet in the upper lefthand portion, the phonograph speaker and equipment cabinet is on the righthand side of the device while the desk portion consists of the left top portion.

I claim:

The ornamental design for a combined radio cabinet, phonograph cabinet, and secretary, substantially as shown, and described.

WILLIAM J. GILLULE.
